Attorney.

UNITED STATES PATENT OFFICE.

CHARLES PAY, OF PROVIDENCE, RHODE ISLAND.

TIP-CART VEHICLE.

SPECIFICATION forming part of Letters Patent No. 766,518, dated August 2, 1904.

Application filed June 14, 1904. Serial No. 212,557. (No model.)

To all whom it may concern:

Be it known that I, CHARLES PAY, a citizen of the United States, residing at the city of Providence, in the county of Providence and 5 State of Rhode Island, have invented a certain new and useful Improvement in Tip-Cart Vehicles, of which the following is a specification.

My invention relates to that class of work-vehicles in which the cart-body is arranged to 10 tip in order to unload the contents; and the invention is confined to the reach, and more particularly to an improved construction of hinge for connecting the reach to the axle-bed of the cart-body and arranged so as to permit 15 of readily disconnecting the cart-body from the reach whenever such portions of the vehicle need repairing.

Figure 1 is a top plan view of the running-gear of a tip-cart vehicle as embodying my 20 improvement and also indicating the position of the cart-body in dotted lines. Fig. 2 is a side sectional view taken in line X X of Fig. 1, showing the normal position of the cart-body on the running-gear, together with a 25 dotted position of the cart-body as when tipped to unload. Figs. 3, 4, and 5 are detail views in perspective of my improved hinge for the running-gear of a tip-cart vehicle, Fig. 3 representing one member of the hinge, which is 30 designed to be secured to the reach, Fig. 4 the other hinge member, which is designed to be secured to the axle-bed of the cart-body, and Fig. 5 the pin for connecting both said members together.

35 My invention consists in the combination, with the front and rear axles of a cart-vehicle, of a gooseneck-reach whose forward portion is pivotally connected with the front axle and its rear portion forming a support for the 40 cart-body, which is arranged to tip upon the rear axle, and a hinge for connecting the rear-axle bed to the reach, and of the novel construction and arrangement of parts, as hereinafter described and claimed.

45 Like characters indicate like parts.

In the accompanying sheet of drawings, A represents the reach, whose forward portion is pivotally connected to the front axle *b* in any suitable manner, and said reach has a goose-

neck, as at *e*, so as to permit easy turning of 50 the forward wheels *d d*.

B is the cart-body, which is mounted on the cross-piece or bed *e* of the rear axle *f*, said body, bed, and rear axle being secured together by the bolts *g g*. 55

h is a plate mounted on the rear portion of the reach *A* and secured thereto by rivets *i i*. Said plate *h* has a circular bent portion at one end thereof and which forms an eye, as at *h'* in Fig. 3. 60

j j are bolts having enlarged integral heads *j' j'* at one end thereof and their opposite portions circumferentially screw-threaded to receive a loose washer *j''* and nut *j'''*, respectively. 65

The bolts *j j* are made secure in the rear- 70 axle bed *e* and arranged so that their heads *j' j'* embrace the sides of the circular bent portions of the plate *h*. Said bolts *j j* are each provided with a circular opening formed in their heads and of a size to register with the 75 eye of the plate *h*.

The plates *h h* and bolts *j j*, which form my 80 improved hinge members, are connected together by pins *k k*, which pass loosely through the eyes or openings formed therein, and said pins *k k* have each an enlarged integral head *k'* formed at one end thereof and their opposite portions screw-threaded to receive a nut *k''* for securing the pins in place in the manner shown in Fig. 5. 85

In the ordinary construction of a tip-cart vehicle a U-shaped bolt or staple is used for connecting the axle-bed to the reach, and which mode of connection often involves considerable labor to withdraw such a part from 85 its place in order to detach the cart-body from the reach to make repairs.

By my construction of hinge it will be easily understood that all that is required on the part of the mechanic is the simple unscrewing of the nuts *k''* and withdrawing the pins *k*. Furthermore, by applying a gooseneck-reach to the running-gear of a cart-vehicle whose body is arranged to tip it is evident that this class of vehicle can easily be turned around 95 in cellars or in narrow quarters where excavations are being made.

Having described my improvement, what I

claim, and desire to secure by Letters Patent, is—

In a tip-cart vehicle, the combination with the front and rear axles, of a gooseneck-reach 5 whose forward portion is pivotally connected to the front axle and its rear portion forming a support for the cart-body, which is arranged to tip upon the rear axle; a hinge comprising a plate secured upon the rear portion of the 10 reach and having at one end a circular bent portion so as to form an eye; bolts adapted to be secured in the axle-bed of the cart-body

and said bolts having enlarged integral heads which are each provided with a circular opening arranged to register with the eye in said plate; and a pin for securing said bolts to said plate, substantially as shown and for the purpose specified. 15

In testimony whereof I affix my signature in the presence of two witnesses.

CHARLES PAY.

Witnesses:
